UNITED STATES PATENT OFFICE

WILLIAM HENDERSON AND JOHN J. HENDERSON, OF PHILADELPHIA, PENNSYLVANIA

DESIGN FOR A RUG

Application filed April 1, 1929. Serial No. 30,714. Term of patent 7 years.

To all whom it may concern:

Be it known that we, WILLIAM HENDERSON and JOHN J. HENDERSON, citizens of the United States, residing in the city and county of Philadelphia, State of Pennsylvania, have invented a new, original, and ornamental Design for Rugs, of which the following is a specification, reference being had to the accompanying drawing, forming part thereof.

The figure is a plan view of a rug showing our new design. The design illustrated constitutes practically one-half of the rug, and the design is repeated at the opposite end.

We claim:—

The ornamental design for a rug, as shown and described.

WILLIAM HENDERSON.
JOHN J. HENDERSON.
